UNITED STATES PATENT OFFICE.

JOHN FAULDS, OF OAK PARK, ILLINOIS, ASSIGNOR TO MIDDLEBY OVEN MFG. CO., A CORPORATION OF ILLINOIS.

BAKE-OVEN.

No. 910,465.

Specification of Letters Patent.

Patented Jan. 19, 1909.

Application filed October 11, 1907. Serial No. 396,997.

To all whom it may concern:

Be it known that I, JOHN FAULDS, a subject of the King of Great Britain, and resident of Oak Park, county of Cook, and State 5 of Illinois, have invented certain new and useful Improvements in Bake - Ovens, of which the following is a specification and which are illustrated in the accompanying drawings, forming a part thereof.

10 The invention relates to ovens used by bakers, and particularly to the door and illuminating device for such ovens, its object being to provide a simple, inexpensive and convenient door which in its operation will be 15 in part controlled by and will operate a damper for controlling a flue for carrying off the vapors escaping from the door when opened, and which will also automatically control the illuminating device.

20 The invention consists in the structure hereinafter described, and which is illustrated in the accompanying drawings, in which,—

Figure 1 is a detail plan section of the oven 25 taken above the door; Figs. 2 and 3 are detail sections on the line 2—2 of Fig. 1, the one showing the door closed and the other showing the door open; Fig. 4 is a detail plan section on the line 4—4 of Fig. 2; Fig. 5 is a detail 30 tail front elevation of the oven, including the door; Fig. 6 is an inverted plan section of the door casing; Fig. 7 is a detail section of the lamp and its casing; and Fig. 8 is a detail of the same parts, showing the reflector and its 35 mountings.

The front face 10 of the oven is shown as of corrugated sheet-metal, and as covering a wall 11 of masonry.

The front of the oven is represented at 12, 40 and its roof at 13, the roof being covered with sand, as is usual in ovens of this type.

The door opening is shown as in the front 45 wall of the casing, and is inclosed by a metal casing 15 having flanges 16—16 overlapping the front face of the oven, and side walls 17—18 which extend inwardly and converge, a floor plate 19 and a roof plate 20. The door 21 swings inwardly on horizontal pivots which engage the side walls of the casing, and 50 is controlled by a suitable handle 22, preferably extending outwardly beyond the front face of the oven.

A gas flue 23 is located within the walls of the oven above the door casing, and is connected in any suitable way with an oven flue,

not shown. The flue 23 is provided with an induction port 24 opening through the roof plate 20 of the door casing to receive the gases which may issue from the oven upon the opening of the door. This port 24 is 60 covered by a damper 25 pivoted at 26 adjacent the front of the door casing and swing- 65 ing downwardly. The damper 25 is pro- vided with backwardly - projecting fingers 27—27 engaged by arms 28 extending up- wardly from the door 21, whereby the damper is controlled by the movement of the door, closing and opening with it.

The damper 25 is in the form of a heavy 70 block, and serves as a counterweight for the door, its function as such being to facilitate the opening of the door and to hold it in its open position, as shown in Fig. 3. The finger 27 and arm 28 are so shaped and dis- posed that when the door is closed the arm 75 is brought to a central position, thereby serving as a lock against the gravity of the damper.

The light for illuminating the oven is shown as a gas burner 29 supplied by a pipe 80 30, and controlled by a valve 31 actuated by means of a crank arm 32 connected by means of a link 33 with a crank arm 34 at- 85 tached to one of the door pivots 35, so that the opening and closing of the door will open 85 and close the gas valve, the latter being, as usual, so arranged that the closing of the door will not entirely extinguish the light.

The light is inclosed within a casing 36, 90 which is attached to the door casing and has an opening to the oven. This opening is cov- 95 ered by an inwardly-swinging opaque screen or shield 37 and a laterally-projecting arm 38 which extends into the path of the door 21, whereby the opening of the door will also open the light casing or lantern.

The side walls 17—18 of the door casing are apertured to provide access to the lantern 36, which may be located at either side of the door casing, being so made that it may be set 100 either side up, according to the side of the door upon which it is placed. The shield 37 is, for the same purpose, provided with an additional lateral arm 39 extending in the opposite direction from the arm 38 for the 105 purpose of engagement with the door when the lantern is upon the opposite side thereof from that in which it is shown in the draw- 110 ings. A plate 40 may be applied to that side of the door casing, as 17, which is not, in the

oven as constructed, coöperating with the light.

A reflector 41 is pivotally supported by a bracket 42 formed on the side wall of the light casing or lantern 36, and may be swung into opposite position back of the burner 29, as shown in Fig. 4, or may be turned backwardly to give access to the burner from without.

10 I claim as my invention—

1. In a bake-oven having a door opening and a gas-flue induction port in front of the door opening, a vertically swinging door for the opening, and a gravity opening damper for the flue-port interlocked with the door to counterbalance it.

2. In a bake-oven, in combination, an upwardly opening door, and a downwardly opening gas-flue damper, the door and the damper being interlocked to move simultaneously and arranged to counterbalance each other.

3. In a bake oven, in combination, a vertically swinging door and a vertically swinging gas flue damper, such parts being interlocked to counterweight each other, one of such parts opening downwardly and the other opening upwardly and being arranged to open simultaneously and to close simultaneously.

4. In a bake-oven, in combination, an upwardly and inwardly swinging door, a down-

wardly opening gas-flue damper interlocked therewith, and an upwardly opening lantern shield carried by the door.

35

5. In a bake-oven, in combination, an upwardly and inwardly opening door, and an upwardly opening lantern shield having an arm projecting into the path of the door.

6. In a bake-oven, in combination, an upwardly and inwardly swinging door, and an upwardly swinging lantern shield carried by the door.

7. In a bake-oven, in combination, a swinging door, and a swinging lantern shield, the two members being interengaged to open and close in unison.

8. In a bake-oven, in combination, a swinging door, and a swinging gas-flue damper, the two members being interengaged to counterweight each other and to move together, but in opposition.

9. In a bake oven having a door opening and a gas flue induction port adjacent such opening, in combination, a vertically swinging door for the opening, and a gravity-opening damper for the flue port interlocked with the door to counterbalance the same, such parts being so arranged that the damper is locked against movement when closed.

55 JOHN FAULDS.
